NEBULIZING INHALATOR FOR
MEDICATIONStanley L. Fox and Charles C. Coghlan,
Los Angeles, Calif.

Application May 19, 1937, Serial No. 143,511

3 Claims. (Cl. 128—194)

Our invention relates to an inhalator for a liquid medicament in which such medicament in a partially or completely atomized or vaporized form is drawn into the mouth, throat or lungs or the nasal passage during the inspiration. There have been a number of instruments devised and used which attempt to apply a liquid medicament in this finely divided form on the air ejector principle in which air is forced under pressure past the end of an aspirating tube or the like which dips into the liquid medicament. A disadvantage of any type of instrument of this latter character resides partly in the fact that it is difficult for the user, designated the patient, to judge accurately the pressure and the flow of air necessary to secure a proper atomizing or vaporizing of the medicament. Another disadvantage is that if an application of the medicament is made to the mouth, throat or lungs or to the nasal passages through the nose, the patient has an involuntary reaction against inhaled air with the vapor and tends to resist drawing this into the throat or lungs or the nasal passages. Even if medication by such a device is administered by a doctor or a nurse, it is difficult for them to judge the pressure of air necessary and the amount of air flow which should be developed to give a proper atomizing spray timed with inspiration so that the medicament may be applied internally in the desired manner. Most of the devices operated by a pressure air flow utilize a rubber expansible and contractable bulb as a pump but even if the medication is administered by such means in the hands of the nurse, the patient involuntarily reacts against the forcible entrance of the atomized stream and thus the medicament is not properly carried and distributed to the place desired. This particularly applies to any applications of a medicament to the lungs or to the throat.

A main object therefore of our invention resides in an inhalator in which during the inspiration of the breath the patient may draw in by suction the desired liquid medicament either in a partially or completely vaporized form by inhaling through the mouth or the nostrils. This action creates an air flow by suction through the instrument so that the action is developed by the inflow of air over the end of the aspirating tube extending into the liquid medicament and draws a minute jet of the liquid into the air inhaled because of the negative pressure developed. This causes the fine atomizing or vaporizing of the liquid medicament so that only a vapor with or without extremely minute particles or globules is

drawn into the mouth, throat or lungs or into the nasal passages. All the air taken in through the instrument during an inhalation comes in intimate contact with the finely atomized medicament giving a substantially larger concentration than possible by any other means.

A characteristic of our invention resides in part in providing a relatively large space or area for the inflow of air under suction of inhaling in breathing, tapering such opening toward one or more small orifices from which the air enters the vaporizing chamber at relatively high velocity. This is sufficient when passing over the open jet end of a tube extending into the liquid to cause a fine jet or stream of the liquid to be ejected into the air flow. The action of the relatively high velocity flow of air under suction and the much slower velocity flow of the liquid through the fine tube causes an initial breaking up or atomizing of the liquid, this producing the so-called nebulizing effect. As the whole action is controlled by voluntary inspiration the user or patient thus has a direct control of the amount of vapor which will be drawn into the mouth or through the nose. Thus when it is desired to treat the throat bronchial tree or lungs with a medicament, the act of inhaling draws in a sufficient amount of air and at the same time atomizes and vaporizes the liquid and causes its even distribution in the nose, or throat, bronchial tree and lungs. After the initial nebulization further vaporization of the liquid occurs from the passage of air stream over the surfaces which expose the fluid to such action as well as from the expansion of the air vapor and globules as it passes the Venturi throat or baffles, such action being mainly in the upper or dome part of the instrument.

Our invention is illustrated in connection with the accompanying drawing, in which:

Fig. 1 is a vertical section which may be considered as taken on the vertical section line 1—1 of Fig. 2 in the direction of the arrows.

Fig. 2 is a horizontal section on the line 2—2 of Fig. 1 in the direction of the arrows.

Dealing with the construction of Figs. 1 and 2, in our invention we employ a medicament reservoir structure 11 which includes a cylindrical tube 12 having at the bottom a thickened collar 13 with a cone shaped wall 14 extending upwardly having a horizontal upper end 15. This is provided with a plurality of small air intake ports 16, four of these being illustrated. The air passing through these ports operates on the ejector principle to draw liquid through the small

bore tubes 17 which have a jet end 18 preferably formed beveled. These tubes are attached by a cemented connection 19 to the upper end 15 of the conical bottom or base 14. The lower end 20 of each tube is provided with an opening located in proximity to the angle formed by the cone shaped bottom 14 and a cylindrical outer wall 12. There is thus provided an annular reservoir 21 for the medicament. The liquid in this should always be below the top of the transverse portion 15 of the bottom. A distributing tube 25 has a cylindrical lower section 26 with a threaded connection 27 to the upper end of the tube 12. Tube 25 has a contracted neck 28 forming a Venturi type of throat 29. An upper cylindrical section 30 terminates with a closed dome 31. An air suction pipe 33 leads through the dome and preferably has a beveled end 34 with the bevel extending upwardly and thus having the lower portion somewhat pointed as indicated at 35 extending well beyond the axial center of the tube sections 26 and 30 and the Venturi forming section 28. This produces an under-surface 36 of the suction air tube on which globules of liquid may collect and condense. Preferably flexible pipe or tube 37 is connected to the outer end of the fixed pipe 33 and this may have a suction end piece for inserting in the mouth or connecting to either or both of the nostrils.

Although the device may be used as above described, however, we prefer to have the air intake through a flutter valve construction designated by the assembly numeral 40. This employs a cylinder 41 having a threaded connection at 42 to the thickened collar section 13 at the lower part of the reservoir. At the lower end of the cylinder there is an annular valve seat 43 leaving a circular valve opening or port 44. A disc-like flutter valve 45 is seated on the annular seat 43 and is maintained pressed downwardly by a coil compression spring 46 which bears at its upper end against the end of the collar 13 of the upper part of the instrument and at its lower portion on the valve disc 45.

The operation of the device including the flutter valve is as follows: It will be understood that on account of the threaded connection at 42 a slight adjustment may be made as to the compressible action of the spring 46. Thus when the flutter valve construction is slightly unthreaded the spring pressure is less than when the threaded connection is made tight. This gives a slightly variable action in the flutter valve. After the instrument has been filled to the proper level with the medicated liquid which may be either poured through the fixed pipe 33 or may be inserted after unthreading the connection at 27, then when air is sucked into the mouth or nostrils through the pipes 37 and 33, during inspiration of the breath, a partial vacuum is created in the relatively large chamber in the distributing tube 25. This, on account of the open port 16 likewise produces a partial vacuum above the flutter valve disc and causes this to raise, allowing inflow of air. On account of the relatively large area the velocity of flow of this air is comparatively low, however on account of the converging air path due to the conical bottom 14, the velocity is increased and the air flows through the ports 16 at a relatively high velocity. This causes an ejector action in regard to the liquid in the annular reservoir 21, such liquid being drawn up through the small bore tubes 17 and as the jet openings 18 are directly over the center of each air port

16, globules of the liquid are immediately carried off by the inflowing air stream developed by suction. This action causes an atomizing of the liquid producing a nebulous type of vapor. In 5 the formation of the vapor if the air suction is too great small globules of the liquid are carried upwardly, that is, in part impinge on the contracted throat portion 28 and flow downwardly on the inside wall of the distributing tube 25 and thus flow into the reservoir 21. However, due to the Venturi type action of the contracted throat 29, a relatively high velocity is produced 10 through this throat. This brings the air into intimate contact with the minute globules of liquid which have been elevated against the force of gravity and causes these to be broken up in the air stream into more minute particles. In addition the crowding action of the air flow with the liquid passing through the Venturi type of 15 throat brings the larger globules into contact with the lower portion of the neck 28 and these globules flow downwardly on the cylindrical portion 26 and the wall structure 12 into the reservoir 21.

20 An additional action of distribution takes place in the upper portion 30 of the tube 25 as above the Venturi throat to an expansion of the upwardly flowing air. This tends to allow separation of any large globules of liquid. Some of 25 these come in contact with the wall 30 and flow downwardly. Other large globules strike the under portion 36 of the tube 33 and as the beveled inner end 34 slopes upwardly the vapors passing through the tube 30 are very finely 30 atomized and practically without any large globules of liquid. Thus the liquid medicament is given a more even spread on entry in the mouth or through the nasal passages. The action of the flutter valve is to allow entry of a 35 quantity of air, this acting against the compression of the spring 46. The spring then reacts to close the valve which again opens when the vacuum inside the instrument increases. Thus 40 there is an intermittent inflow of the air which 45 develops an improved action of the ejector in elevating the liquid from the reservoir and in the atomizing of such liquid. However it is to be understood that if desired the flutter valve construction may be removed from the instrument or the instrument may be made without provision for attaching such valve in which case the air flows inwardly through the relatively large annular collar 13.

55 The chamber above the throat or Venturi construction of Fig. 1 acts as an expansion chamber in which liquid globules may condense, some of these contact the wall and are then subjected to an evaporating action due to the air passing over such small globules. The action of vaporization of the liquid medicament by the suction which creates a minus pressure is one of slight refrigeration in which the air entering the mouth or nostrils is slightly cooler than the air flowing in through the instrument. Therefore 60 it will be understood that where a hot or warm application of medicament is desired that the air may be heated before being drawn into the instrument by suction or as is a more or less common practice, there may be an intermediate chamber between the patient and the inhalator, the patient by suction drawing the air and medicament through such intermediate chamber which may be heated to apply hot applications. Where cold applications are required,

manifestly this intermediate chamber could be chilled. In some cases it is also desirable to have a washing action of certain medicaments by bubbling the air through water or other washing solution contained in an intermediate chamber. The action of the flutter valve is to intermittently increase the vacuum and thus assist in vaporization of the liquid, hence increasing the concentration of the medicament in the air stream.

The method of operation of our inhalator involves the creation of a partial vacuum or negative pressure in the hollow body structure solely by air inspired in breathing either through the mouth or nostrils. This creates a positive air flow from the outside atmosphere which operates on the liquid medicament in the reservoir. By providing the small bore ejector tube or tubes, the partial vacuum created in such tubes by the flow of air thereover on the operation of suction creates the positive elevation of the liquid from the reservoir into the air stream. At first the liquid leaves these small bore tubes in the form of small globules producing an atomized effect. As these globules come in contact with the air flowing at different velocities and the more or less turbulence of the air as well as by impinging on the sides of the body structure, they become broken up and form a medicated vapor which on being drawn into the mouth or nostrils and on the further inhalation will operate to carry the medicament to the mouth, nasal passages, the throat, bronchial tree and lungs. Thus the sole act of inhaling changes the form of the liquid carrying the medicament into an atomized and vaporized form.

An important characteristic of our invention resides for instance as to the construction of Fig. 1 in providing an annular reservoir with the bottom of the inhalator having an upwardly sloping wall, this being the wall 14 which is cone shaped. Such provides a relatively large opening or channel for the inflow of air which air enters through the plurality of small ports 16. As these ports are located in the upper horizontal end 15 of the bottom structure they may be located but slightly above the level of the liquid in the reservoir therefore the small bore injector tubes 17 may have their orifice or jet end 18 positioned but slightly above the liquid. Therefore on the inflow of air entering through the plurality of ports it is only necessary that the liquid be elevated by suction a comparatively short distance. This produces a plurality of atomized streams of the medicated liquid and these streams mingle together, the medicated vapor thus being taken by the patient through the mouth or through the nose into the bronchial tract and lungs. In cases where the patient finds difficulty in breathing, that is, inhaling, the flutter valve assembly 40 may be removed.

Our invention is particularly valuable in treatment of patients afflicted with asthma of the type which causes difficult breathing. With such patients inhalation is not only difficult but tires the muscles of the diaphragm and accessory breathing muscles, therefore it is necessary to give the relief with as few inhalations as possible. With our invention a medicament may be used in solution with the water which is practically no more volatile than the water itself and thus the medicament has the characteristics of being a mild drug and on account of the construction of the inhalator, at each inhalation there is the mixing of the plurality of jets or

streams of the atomized water with the liquid medicament. In most of the inhalators patented or now on the market, insufficient provision is made for operation by inhalation by the patient and hence it is customary with such devices to use readily volatile solutions of the medicament and these are too potent and too irritating and toxic to the lungs and other tissues reached through the mouth and nostrils.

10 Various changes may be made in the details of the construction without departing from the spirit or scope of the invention as defined by the appended claims.

We claim:

1. An inhalator comprising in combination a hollow body structure having a large air flow channel at the bottom with a wall extending inwardly and upwardly from the bottom and provided with a thin top wall at the upper end of said channel, such wall having a plurality of small air inlet ports of short length with their axes parallel and directed parallel to the longitudinal center of the hollow body structure, said upwardly extending wall and the lower portion of the body structure defining an annular reservoir for a liquid medicament, and an injector means having a jet orifice positioned above and in alignment with each port with an intake for liquid extending downwardly to dip in the reservoir, the upper part of the hollow body having an inhalation suction means to be operated solely by inhalation through the mouth or nostrils, such inhalation creating an upward flow of air through the channel at the bottom, the velocity of the air through the channel increasing towards the top and further developing a fine stream of air through each inlet port directed upwardly and parallel one to the other, the velocity of flow through each port being much higher than the velocity in the channel, the flow of air through the ports developing an ejector action at each ejector orifice causing an atomizing of the liquid medicament in a plurality of upwardly flowing parallel streams, such streams being adapted to mix in the upper part of the hollow body, such medicament being carried upwardly with the flow of air to be inhaled through the mouth or nostrils into the bronchial tract and lungs producing a local as well as a systematic reaction by absorption into the blood stream, a flutter valve device connected at the bottom of the hollow body structure and below the entrance end of the air flow channel, such flutter valve device having a valve opening with a valve seat 55 and a flutter valve disk, a compression spring seating the disk on the seat adjacent the opening, the spring being tensioned to maintain the flutter valve closed until a desired degree of vacuum is created in the hollow body structure, such vacuum by producing a negative pressure facilitating the vaporization of the liquid, the spring having the characteristic of yielding at a higher degree of vacuum and admitting air to carry the evaporated liquid to the inhalation suction means and then on the increase of internal pressure 65 the spring again closing the flutter valve and during inhalation developing an intermittent action of opening and closing the valve.

2. An inhalator comprising in combination a hollow body structure having one or more inlet air ports, the bottom of the structure forming a reservoir for a medicament, an injector means having a jet orifice positioned in alignment with the port or ports and having an intake end extending into the reservoir, an air suction outlet

remote from the port and orifices, a flutter valve construction connected to the bottom of the body structure and having a spring closed valve operative to open on a partial vacuum being created in the hollow body structure by inhalation and to close when the internal pressure is increased and thereby develop an intermittent opening and closing of the flutter valve during a continuing inspiration through the suction pipe.

3. An inhalator comprising in combination a closed hollow body structure having an air flow channel at the bottom including a wall at the upper end of such channel, an air port extending through such wall, there being a reservoir below the said wall for a liquid medicament, an injector means having a jet orifice positioned above and in alignment with the port with an intake for liquid in the reservoir, the upper part of the hollow body having an inhalation suction means to be operated solely by inhalation through the mouth or nostrils, a flutter valve device connected

5 at the bottom of the hollow body structure and below the entrance end of the air flow channel, such flutter valve device having a valve opening with a valve seat and a flutter valve disk, a compression spring seating the disk on the seat adjacent the opening, the spring being tensioned to maintain the flutter valve closed until a desired degree of vacuum is created in the hollow body structure, such vacuum by producing a negative pressure facilitating the vaporization of the liquid, the spring having the characteristic of yielding at a higher degree of vacuum and admitting air to carry the evaporated liquid to the inhalation suction means and then on the increase of internal pressure the spring again closing the flutter valve and during inhalation developing an intermittent action of opening and closing the valve.
